DESIGN FOR A HAT

David C. Everitt, Milwaukee, Wis.

Application November 25, 1938, Serial No. 81,332

Term of patent 3½ years

To all whom it may concern:

Be it known that I, David C. Everitt, residing at Milwaukee, in the county of Milwaukee and State of Wisconsin, have invented a new, original, and ornamental Design for a Hat, of which the following is a specification, reference being had to the accompanying drawing, forming part thereof.

In the drawing:

The characteristic feature of my design resides in a hat of the configuration shown having a plain brim and a crown composed of contrasting rings of substantially equal widths and of the specific configuration and arrangement as shown.

I claim:

The ornamental design for a hat, substantially as shown and described.

DAVID C. EVERITT.
